UNITED STATES PATENT OFFICE.

WILLIAM F. THORNTON, OF BIRMINGHAM, ALABAMA.

UNLOADING APPARATUS.

1,272,150.

Specification of Letters Patent. Patented July 9, 1918.

Application filed June 10, 1915. Serial No. 33,331.

To all whom it may concern:

Be it known that I, WILLIAM F. THORNTON, a citizen of the United States of America, residing at Birmingham, in the county 5 of Jefferson and State of Alabama, have invented certain new and useful Improvements in Unloading Apparatus, of which the following is a specification.

My invention relates to new and useful 10 improvements in an unloading apparatus which is particularly designed and adapted for the unloading of material that is customarily handled in slings from boats and delivering it to the dock or warehouse for 15 further distribution.

My apparatus contemplates the use of a 20 traveling structure adapted to move lengthwise of the dock and having mounted thereon a truss along which an endless conveyer passes and from which it drops into the hold 25 of the vessel to be unloaded. An important problem in apparatus of this character is the adapting of the truss to be so manipulated that it can be adjusted into position 30 over the hatches of various types of vessels without interfering with their rigging and without regard to the stage of the water. Extreme flexibility of adjustment is required 35 in this respect of the truss and an important feature of my invention is directed to the novel means to attain this end without unnecessarily complicating the construction or affecting its strength or the ease with which it can be controlled.

Other features of my present invention 40 are the novel design of the truss supporting structure and the manner of adjustably supporting the truss therefrom; the novel arrangement for taking up and letting out the endless conveyer for service at different 45 levels in the hold; the provision of one or more handling lines independently controllable to drag the freight from different parts of the hold to the conveyer; the novel arrangement of the operators' platforms 50 which are swung from the outer end of the truss; and various other details which are hereinafter more particularly described and set forth in the appended claims.

As illustrative of what I consider the preferred embodiment of my invention, reference is made to the accompanying drawings which form a part of this specification, and in which:

Figure 1 is a diagrammatic view in side

elevation showing the apparatus in service with the truss in its extreme outer position.

Fig. 2 is an enlarged detail view in side elevation of the truss.

Fig. 3 is a front elevation of the movable 60 structure with the truss shown in cross section on the line 3-3 of Fig. 2.

Fig. 4 is a top plan view slightly reduced 65 of Fig. 3 with the driving mechanism on the structure omitted for the sake of clearness.

Fig. 5 is an outer end view of the truss as seen in Fig. 2 with the boom omitted.

Fig. 6 is a detail view of the take up 70 sprockets with the mechanism for detachably interlocking them.

Figs. 7 and 8 are diagrammatic views 75 showing the truss in its several adjusted positions and illustrating the flexibility of its control.

Fig. 9 is a vertical sectional view 80 through one of the swinging operators' platforms at the outer end of the truss and illustrating the manner of its connection to the truss and the mechanism controllable 85 therefrom.

Similar reference numerals refer to similar parts throughout the drawings.

The main truss supporting structure 85 consists of a frame work, preferably of steel, which is pyramidal in elevation and is supported on wheels 1 which travel on rails 2 running lengthwise of the dock, thus permitting the entire structure to move freely to any desired location along the dock. A steel 90 truss 3, of sufficient length to extend over the center of the hatchways of the largest boat, is supported at its inboard or shore end on two flanged wheels 4, which in turn rest on horizontal rails 5 fixed on each side of a vertical passageway or tunnel 6 in the structure. The outer end of the truss is pendent from the boom 7 by an adjustable block and tackle comprising a lower pulley 8 fast on the outer 95 end of the truss and an upper pulley 9 suspended by a swivel hanger 10 from the upper end of the boom 7. A line 11 made fast to the swivel passes around these pulleys and is carried to the side of the boom so as to clear the truss, a pulley 12 being mounted on 100 the side of the boom to receive the line and from this pulley the line extends downwardly along the bottom to a pulley 13 mounted on a forward portion of the structure and disposed concentric with the axis 15 105 110

on which the boom swings. The boom itself, as seen in Fig. 3, is divided into two parts which comprise inner parallel bars 16 and outer bars 17, each inclined toward the adjacent bar 16 and braced thereto by lattice-work. The two bars 16 at their upper ends are cross connected by a bar 18. The bars 16 have their pivot points or axes 15 mounted on an I-beam 19 forming the bottom of the well 6 and rigidly supported on a bent 20 of the structure. The structure comprises inner inclined braces 20 to take the thrust strain of the boom. By this arrangement the parted boom leaves the well 6 in the structure unobstructed in front for the adjusting play of the truss 3 therein. The tracks 5, upon which the truss wheels 4 travel, are mounted on I-beams 21 which extend through the well on each side thereof and project to the front and rear of the structure proper being supported at their outer ends at each side by spaced pairs of vertical beams 22 and 23 disposed respectively at the front and rear of the structure and mounted thereon and braced thereto. Side brackets 21^a support the beams 21 in the well. This arrangement is perhaps more clearly shown in Figs. 1, 7 and 8, where the truss track support is shown clearly as a rectangular frame which extends horizontally through the pyramidal structure at an intermediate point so that the structure projects vertically and centrally above it. This arrangement is of particular advantage in making the structure very simple and at the same time providing the most convenient means for the strong support and flexible control of the truss 3. The line 11, for raising and lowering the outer end of the truss relative to the boom, after passing the pulley 13 is carried up along the structure and after passing around a pulley 24 at the top of the structure it passes to a drum 25 mounted above a suitable platform 26 above the well 6. A line 27 leads from another drum on said platform 26 and after passing around pulleys 29 and 30 at the top of the pyramidal structure and at the upper end of the boom is made fast so that the boom can be raised and lowered on its axis 15. These drums 25 and 28 are loose and provided with the ordinary friction clutch and brake means (not shown) for driving them from a pulley 31 which is driven by a belt or chain 32 from a pulley 33 which in turn is driven by a pulley 34 and belt 35 from the motor 36 at the bottom of the structure. This belt 35 drives a plurality of independent clutch controlled pulleys, one of which serves to drive by means of a belt 37 the worm shaft 38 which, through a worm 39 on the axle 40 for the wheels, controls the adjustment of the structure on its track. Another of said pulleys, by means of a belt 41 and gearing

42, serves to drive an endless conveyer 43 which receives the unloaded material from a chute 44 and delivers it to a distributing platform or shed 45. This driving mechanism is not illustrated in detail because it really forms no particular part of my present invention as the several moving elements may be driven in any approved fashion and by any suitable mechanism in a manner which is commercially well understood. 75

An important feature of my invention is the truss or bridge 3 which, as illustrated more clearly in Figs. 2 and 3, is an elongated structure rectangular in transverse cross section and formed by four longitudinal chords 46 braced together by side lattice-work 47 and by top and bottom lattice-work 48, thus forming a hollow brace truss possessing great strength for its weight. The wheels 5, on which the inboard end truss is mounted, are connected to axles 49 which are journaled in angle irons 50 fastened to the lower chords 46. Near its outer end I make fast to the upper chords 46 two uprights 51 upon which is mounted a transverse bar 52 carrying at its center the journal bearing 53 for the pulley 8. On the extreme outer ends of the upper chords 46 I mount journal bearings 54 (see Figs. 2 and 5) and in these bearings I mount a shaft 55 which has fast thereon between journals a pair of spaced sprockets 56 and which has on its outer end which projects beyond the side of the truss a sprocket 57 keyed thereon and adapted to be driven by a chain 58 from a sprocket 59. This sprocket is keyed to a cross shaft 60 which extends through and is suitably journaled in the truss and which at its outer ends serves as a trunnion bearing for the swinging platforms 61 which will be hereinafter more particularly described. This shaft 60 has fastened thereon a sprocket 62 which is disposed within the truss and is driven by a chain 63 passing lengthwise through the truss and about a sprocket 67 at the rear end of the truss. This driving mechanism, rigidly supported at the inboard or shore end of the truss, consists of the following: A motor 65 drives the countershaft 66 on which are a sprocket 67 and a bevel gear 68, the latter driving shaft 69 through bevel gear 70. On the shaft 69 is a worm screw 71 driving a worm wheel 72 on a shaft 73. On this shaft are coupled sprockets 74, driven by a jaw clutch 74^a, for driving the conveyer chain 75 and a sprocket 76 driving sprockets 77 through a chain 78. Two strands of endless chain 75, provided with hooks 76 spaced at proper intervals, pass around driving the sprockets 74, take up wheel 79 and smooth face idlers 80, operating on angle rails 81 inside the truss, drivers 77 and 56, and an idler sprocket 82 (which is weighted sufficiently to prevent undue swaying when loads are picked up 130

by chains) idler sprockets 83 and back to driving sprockets 74. The sprockets 83 are mounted on a shaft 84 journaled in bearings 54 attached to the underside of the truss. 5 The take up wheels 79 and the smooth face idlers 80 are respectively mounted on cross shafts 88 and 89. The shaft 88 at its end is mounted in slide blocks 90 which travel in slideways formed between the adjacent 10 horizontal flanges of angles 81 supported by brackets 81^a for the top of the truss. In like manner the shaft 89 is mounted in slide blocks 91 which move similarly in the guides 81. The shaft 88 at each end is connected 15 by a bail 92^a to a line 92 which runs forward through the truss to a drum 93 mounted on a countershaft 94 at the forward end of the truss, which shaft is driven by a sprocket 95 and chain 96 from a sprocket 97 on the 20 shaft 60. A clutch 97^a controls the driving of sprocket 97. The drum 93 is adapted to be driven with the shaft 94 by means of a clutch 98 and may be provided with a suitable brake 98^a. 25 Referring to Fig. 6, it will be noted that the blocks 90 carry rearwardly extended hook members 99 with their hook ends downturned and that the blocks 91 have hinged thereto latch members 100 with an upturned 30 detent adapted to interlock with the hook 99 and with a downturned tapered point 101 adapted to drop into a socket 102 in the lower guides 81 and permit the hook and detent to automatically disengage, leaving 35 the idler 80 at an intermediate point in the truss while the take up sprocket 79 may be moved to the extreme position at the outer end of the truss shown in Fig. 1. As the take up 79 is caused to move inwardly along 40 the truss its hook member 99 will pass over the detent when in its notch 102 and will engage the blocks 91 so as to move the take up sprockets and idlers together to their inner position shown in Fig. 2. The idlers 80 45 serve as supports for the chain 75 when the take up sprockets are in extreme outer position, as will be more clearly seen in Fig. 1.

In order to facilitate the collecting of the freight so that it can be conveniently loaded 50 onto the chain 75, I provide a pair of handling lines 103 having hooks 104 at their lower ends. These lines are wound on drums 105 which are loosely mounted on the shaft 60 at the outer end of the truss and 55 each drum is controlled by independent clutch members 106 and by a brake 106^a.

A platform or cage 61 for the operators is freely suspended on each side of the outer end of the truss 3 in such manner that the 60 floor will remain always horizontal without regard to the angular disposition of the truss. This is preferably provided for by counter-weighting the bottom of the platforms at 107 and by mounting the platforms 5 at 107 and by mounting the platforms 108 on the outer

ends of the shafts 60. The right hand cage in Fig. 5 will have a slot in its top 108^a through which the driving chain 58 will pass leading to the sprocket 57. Near the outer ends of the rails 5 I mount stop blocks 109 70 which serve to prevent the rollers 4 from passing endwise off the track as the truss is moved in either direction. An additional operator's platform 110 may be provided at a point near the chute 44 in the structure 75 convenient for an operator thereon to disengage the slings 111 from the chain hooks 76. Any suitable automatic release mechanism can be employed if desired.

In operation, the truss is adjusted lengthwise along its tracks 5 by unwinding or winding the line 27, to raise or lower the boom 7, the line 11 being played out or taken in at the same time if it is not desired to swing the truss vertically. This adjustment will obviously result as the raising or lowering of the boom will change the point of suspension for the truss and cause it to swing bodily horizontally on its tracks. When it is desired to change the angularity 90 of the truss this is accomplished by taking in or letting out the lines 21 and 11, as will be more clearly seen by reference to the diagrammatic views in Figs. 7 and 8, and in making these adjustments it will be obvious 95 that the truss will always adjust itself along its track 5 until the line 11 hangs vertically in line with the lifting strain on the chain 75. With the apparatus thus far described, it is possible to move the truss 3 in or out, 100 or raise or lower the outer end to suit the boat being unloaded, being thereby enabled at all times to place the outer end of the truss over hatch without interfering with the ship's rigging. The handling lines are 105 easily controllable from the operators' cages 61 by means of clutch levers 112 and brake levers 113 which control brakes 106^a, thus permitting the lines to be released or to be wound to draw the load to the conveyer 110 chain and then held in this position until its load is transferred.

In order to provide for the raising and lowering of the idler sprockets 82 to control the length of the chain 75 depending from 115 the truss, the clutch 74^a is thrown to release the driving sprockets 74 and the clutch 98 is thrown to coil the line 93 and draw the take up sprocket 79 to the right, Fig. 2, thereby shortening the chain 75. A brake 120 lever 114 is then operated to apply the brake on the drum 92 and hold the take up sprockets at the desired points. To lengthen the chain 75, the brake lever 114 is released and when the drivers 74 are disconnected, the 125 sprockets 56 are driven to draw the chain 75 about the upper sprockets 77. Operating levers 115 and 116, respectively, control the clutches 77^a and 98.

While I have referred to the structure as 130

having a tunnel or well in which the truss is received and left free for vertical play, it will be understood that this term is meant to include any suitable space provided in the structure which will permit the truss to have the free vertical play contemplated in my invention. I prefer to have the boom which supports the outboard end of the truss mounted on and braced from the structure, but obviously such arrangement is of importance only where the structure is adjustable and it is desirable that all supporting parts should move together.

It will be understood that the principles 15 of construction and operation which I have herein described are capable of many modifications without substantial departure from the true spirit of my invention.

Having thus described my invention, what 20 I claim as new and desire to secure by Letters Patent, is:—

1. In an apparatus of the character described, the combination of a vertically adjustable truss and its supporting structure, 25 of a pair of swinging platforms suspended from the outboard end of the truss, handling lines which drop from the outboard end of the truss, power mechanism on the truss, drums for said lines, clutch controlled means 30 to drive said drums from said power mechanism, means on each platform to independently control a handling line by means of said mechanism, and a conveying apparatus on the truss also driven by said mechanism, 35 substantially as described.

2. In an apparatus of the character described, a truss supporting structure, a truss, means to adjustably support the truss from said structure, a motor mounted on the inboard end of said truss, an endless conveyer 40 mounted on the truss and driven by said mo-

tor, a handling line suspended from the outboard end of the truss, driving connections from said motor to independently operate said line, take-up mechanism for said endless conveyer which is adjustable lengthwise of the truss, mechanism for adjusting said take-up means from said motor, and means for controlling said take-up and handling lines at the outboard end of the truss, substantially as described. 45

3. The combination with an endless conveyer and its supporting and driving mechanism, of adjustable take-up idlers over which said conveyer passes, guides for said take-up idlers, auxiliary supporting idlers which coöperate with the take-up idlers, means to connect said auxiliary idlers and take-up idlers for joint movement when the latter are in initial position, and means to automatically disengage the auxiliary idlers from the take-up idlers when the latter reach an intermediate point in their adjusting travel, substantially as described. 50

4. In an apparatus of the character described, an endless conveyer, and means to support and drive the same, a take-up mechanism comprising an adjustable take-up roll, an auxiliary idler roll, a pivoted latch on the latter, a dog on the former adapted to engage the latch, a track on which engages the latch and holds the dog and latch interlocked for joint movement of the two rolls, and a trip in the track to disengage the dog and latch at an intermediate point in the adjustment of the take-up mechanism, substantially as described. 55 60 65 70 75

In testimony whereof I affix my signature.

WILLIAM F. THORNTON.
